[57] **CLAIM**

The ornamental design for a hands-free speakerphone for automobile, as shown and described.

DESCRIPTION

FIG. 1 is a top view of a hands-free speakerphone for automobile embodying my design;

FIG. 2 is a front view thereof, the rear view being substantially a mirror image thereof;

FIG. 3 is a bottom view thereof;

FIG. 4 is a first end view thereof; and,

FIG. 5 is a second end view thereof.

The cable is shown broken away at the right side in FIGS. 1-3 to indicate in determinant length it being understood that the cable is continuous throughout.
